UNITED STATES PATENT OFFICE.

GEORGE W. COOPER, OF BROOKLYN, NEW YORK.

CUFF.

1,305,067.

Specification of Letters Patent. Patented May 27, 1919.

Application filed May 8, 1918. Serial No. 233,297.

To all whom it may concern:

Be it known that I, GEORGE WASHINGTON COOPER, a citizen of the United States, and a resident of the city of New York, borough 5 of Brooklyn, in the county of Kings and State of New York, have invented a new and Improved Cuff, of which the following is a full, clear, and exact description.

Among the principal objects which the 10 present invention has in view are: to avoid abrasive wear of cuffs; to prolong the service life of articles of clothing in the construction of which the fabric is sharply folded; to strengthen the structure of articles of the character mentioned without 15 increasing the cost thereof; to reinforce structures of the character mentioned while preserving neatness of appearance; and to reinforce said articles without increasing 20 the quantity of cloth required for the construction.

Drawings.

Figure 1 is a side view of a facing section 25 arranged to be incorporated in the structure of a cuff for personal wear, a reinforcing strip being shown in conjunction therewith and as attached thereto;

Fig. 2 is a perspective view showing a 30 fragment of the same, the reinforcing strip being shown in the position in which it is initially disposed on the facing section;

Fig. 3 is a perspective view of the same, showing the reinforcing strip as being 35 turned to cover the seam connecting it and the facing section;

Fig. 4 is a perspective view of the same, showing the fold of the reinforcing strip upon the facing section as completed;

Fig. 5 is a perspective view showing the 40 facing section and reinforcing strip as overlaid by a backing section and lining therefor;

Fig. 6 is a perspective view of the same 45 showing the backing section and lining therefor as in the act of being folded to cover the seam connecting said section and lining with the facing section and reinforcing strip;

Fig. 7 is a perspective view of the same 50 showing the bend of the facing section and reinforcing strip to form the cuff edge;

Fig. 8 is a side view of the completed cuff

constructed and arranged in accordance with the present invention.

55

Description.

In the manufacture of shirts, and particularly in the manufacture of stock shirts, the patterns, according to which the parts are 60 cut, having been designed to avoid waste of the material required. To accomplish this, the material from which the cuffs are made is taken from the "piece" lengthwise or parallel with the warp threads thereof. In 65 striped goods the design of the garment provides for this arrangement, it being desired that the strips in the cuffs shall extend around said cuffs. The result of the method is that the material is bent cross- 70 wise of the woof threads of the fabric. The woof threads of the fabric have usually less tensile strength than the warp threads owing to the obvious manufacturing requirement that the warp threads of the fabric 75 must resist the action of the harness and of the sand roll of the loom, while the woof threads have only to resist the run of the bobbin in the shuttle.

In service, cuffs, and particularly 80 starched cuffs, are called on to resist the abrasive wear on the outer or facing section of the cuff adjacent the edge thereof. Also when the material is starched and laid by the iron, an additional strain is exerted on 85 the threads of the fabric during the operation of flattening the same.

The present invention has for its particular object to avoid this wear, and with this in view, it may be said to consist in arranging the materials composing the cuffs so that the warp threads are bent over in making the fold forming the edge of the cuff. It is to avoid the necessity of constructing the cuff from fabric having warp threads extending lengthwise thereof that there is provided a narrow wearing strip, the warp threads whereof may extend in a manner described, or in directions approximating the same such as when the said wearing strip 100 is cut with the warp threads on the bias.

As seen in the drawings, a cuff constructed and arranged in accordance with the present invention, is provided with a facing section 105, a back section 16, and a filling or lining 17. The facing section and back section are

cut from fabric where the warp threads are disposed crosswise of the cuff or lengthwise of the sections as indicated in the drawings by the strips of the fabric. The section 15 is preliminarily prepared for attachment to the back section 16 and lining 17, by having applied to said section 15, a narrow wearing strip 18. The strip 18 is sewed at one end by a line of stitching 19, as seen in Fig. 2 of the drawings. To receive the back section 16 and lining 17, as shown in Fig. 5 of the drawings, the wearing strip 18 is bent upon itself as shown in Figs. 3 and 4, to cover the stitching 19. When the back section 16 and lining 17 are overlaid upon the strip 18, as shown in Fig. 5, the three edges of the back section, lining and wearing strip are united with the facing section 15, by a line of stitching 20.

20 The parts are now united so that the fold forming the edge of the cuff may be made. This is accomplished, as shown in Figs. 6 and 7, by folding the back section 16 and lining 17, so that the stitching 20 is covered and the bend forming the edge of the completed cuff is made in the facing section 15 and wearing strip 18. When this fold has been completed, as in the usual construction, a seam or line of stitching 21 is made extending through the folded fabrics, to wit, the facing section 15, lining 17, and back section 16 and the edge 22 provided in the facing section 15, beyond the raw edge of the wearing strip 18, as shown best in Fig. 4.

30 35 When the structure formed by the various layers of fabric is now ironed, it will be ob-

served that the service wear upon the cuff is received upon the wearing strip 18.

It is also evident that the wearing strip 18 is bent across the warp threads of the fabric forming said strip, or in a manner producing the greatest resistance to the breaking strain of the iron and to the abrasive effect of the wear to which the cuff is subjected.

45 While there has been herein shown a wearing strip 18 constructed from the body material of which the cuff is composed and cut on the bias, it will be understood that a suitable tape, twilled or other material, may be employed, so that the warp threads thereof are bent over the line of fold in the wearing strip.

55 *Claims.*

1. An article of manufacture as characterized comprising a wearing strip structurally connected with the body of said article and folded over the exposed edge thereof by means of seams concealed in the completed article, said strip being formed of fabric, the warp threads whereof extend transverse said strip and the edge-forming fold thereof.

2. An article of manufacture as characterized having a body portion and an exposed wearing edge, said edge being relatively narrow and united to the body portion with concealed stitching, the warp and woof threads of the body and edge portions being extended in relatively opposite directions.
